PROCESS FOR PRODUCING ANHYDROUS GRANULATION OF A MEDICINALLY ACTIVE WATER-LABILE POWDER

Alfred Charles de Grunigen, Nanuet, N.Y., assignor to American Cyanamid Company, New York, N.Y., a corporation of Maine

No Drawing. Filed Sept. 12, 1958, Ser. No. 760,572

10 Claims. (Cl. 167—82)

This invention relates to a method of granulating moisture-sensitive powders for use in the manufacture of tablets and the tablets so produced. Water permeable ethyl cellulose is used as a binding agent. This case is in part a continuation of my co-pending application Serial No. 687,862, filed October 3, 1957, now abandoned, which in turn is in part a continuation of my co-pending application Serial No. 342,297, filed March 13, 1953, both now abandoned.

In the manufacture of tablets, particularly those containing medicinals, vitamins or nutrients, it has been customary to granulate the dry powder constituting or containing the active ingredient by mixing it with an aqueous solution of a gum, such as gum acacia in water, to form a thick paste which is forced through a coarse screen and permitted to dry, thereby forming granules. These granules are then passed through a finer screen to break them up, mixed with a lubricant such as stearic acid powder or magnesium stearate and/or a talc, and blended thoroughly. The granules are then compressed in a standard tablet compressing machine in which the granules are permitted to flow into a die and a punch brought down to compress the material, thereby forming a tablet, and the completed tablet is then ejected from the machine.

Granulation is necessary because many dry powders will not cohere. Also, if the powder is run through the machine, it bridges or flows unevenly so as to give non-uniform size to the tablets, or forms fragile tablets so that the tablets easily disintegrate into the original powder in release from the forming dies.

In the past, it has been found that certain medicinals, vitamins, nutrients, etc. in the form of powders are sensitive to the moisture used in the granulating solutions so that, accordingly, the powder loses its potency or discolors or is otherwise damaged. Similarly, it has been observed in the past that certain binding agents suffer from the same deficiencies.

According to the present invention, water sensitive powders which either deteriorate in the presence of moisture or otherwise react undesirably, such as effervescent compositions, are granulated by means of a solution of water permeable ethyl cellulose. The granules are useable in standard tabletting machines without substantial change in operating conditions and produce satisfactory tablets.

It is necessary that the solvent for the water permeable ethyl cellulose be substantially nonaqueous. It is also essential that the solvent be volatile and substantially non-reactive with the components to produce disintegration, discoloration or other undesirable reactions and it should not be sufficiently toxic so that minute quantities which remain after evaporation of the solvent would constitute a toxicity hazard.

The solvents found suitable are lower alkanols, such as methanol, ethanol, isopropanol and the like. The alcohols may be completely anhydrous or they may contain

2

a small amount of moisture. For example, commercial 95% ethanol or slightly moist (99%) isopropanol may be used. The small amount of water is so tightly held in these alcohols that it does not react with tablet materials.

5 The solvent should be one which is volatile under conditions under which the powder to be tableted is stable and which is inert towards the powder, and in which the binding gum is soluble. The amount of solvent to be used is such that a paste results in the granulating operation with the individual granules sufficiently firm to maintain their shape and yet sufficiently soft to be forced through the granulating screen. The quantity of binder dissolved in the solvent is such as to result in tablets of a desired solidity. More of the binder results in a firmer tablet. Finer powders usually require more binder and solvent than coarse powders. Mixtures of powders may be granulated together or granulated separately and then mixed. The amount of solvent is usually between about 10 and 40 milliliters per 100 grams of powder, and usually this amount of solvent should contain from 1 to 10 grams of the binding agent, such as water permeable ethyl cellulose.

20 Ethyl cellulose, which is water permeable and has an ethoxyl content of from about 43% to 50%, appears to be uniquely suited. This is not generally true of hydrophilic cellulose ethers. For example, methyl cellulose is quite unsuitable. Tablets produced by granulating compositions containing ascorbic acid with aqueous solutions of methyl cellulose discolor rapidly on exposure to air and are unacceptable. Similar difficulties are encountered with other moisture-sensitive materials.

25 It is not feasible to use ethyl cellulose of too low water permeability. Thus, if water insoluble ethyl cellulose is used, granulation occurs but the tablets are not practically useful as they do not disintegrate in the gastro intestinal tract at a sufficient rate to be practical. It is therefore essential that the ethyl cellulose be water permeable although it is not water soluble. In general, the best ethyl celluloses to be used in the present invention are, as 30 stated above, those having an ethoxyl content of between 43% to 50%. This is not the absolute limit of usefulness as other ethyl celluloses which are still water permeable but not water soluble can be used. In order to avoid awkward language throughout the remainder of the specification and in the claims, the term "water permeable" will be limited to products which can be permeated by water but are not soluble in it. A typical example of a commercial water permeable ethyl cellulose is one having an ethoxyl content of 47% which softens at 140° C. and is soluble in ethyl acetate, ethylene dichloride, benzene, toluene, xylene, butyl acetate, acetone and carbon tetrachloride in addition to the lower alkanols.

35 While the amount of the water permeable ethyl cellulose is not sharply critical, for practical utility the amounts should be between 0.5% and 10% by weight of the solids in the tablet. No single amount of ethyl cellulose will give optimum results with every medicament as the best amounts will vary somewhat with the solubility of the medicament in water. Optimum amounts, however, will 40 always fall within the range given above.

Several methods can be used in formulating the composition of this invention. The method which effects the desired results with the greatest facility involves mixing the active ingredient in the form of a powder 45 with the ethyl cellulose binder, and fillers where necessary, all in the dry state. It is sometimes necessary to screen some or all of the dry ingredients prior to mixing. This mixing step is followed by the addition of the solvent, preferably in small quantities, accompanied 50 by mixing to form a homogeneous paste. On the other

hand, the binding agent may first be dissolved in the solvent; the solution may be assisted by heating the solution. The solution is then added to the powder which is to be tableted; a homogeneous paste is thus formed.

The paste formed by either of the above procedures is then passed through a screen to break it up into granules and the granules are allowed to dry at either room temperature or elevated temperatures. The drying may be expedited by heating in a drying oven (about 35° C. to 50° C.) due caution being used to insure that the fumes do not cause fire hazards or safety hazards to the health of the operator. When drying is effected at room temperature (about 24° C.), a drying time of 12 to 20 hours should be used. When elevated drying temperatures are used, the drying time will be about four to eight hours. After drying, the granules may be passed through a screen to break them up into smaller granules and separate granules which have become adherent to each other, thereby forming a free-flowing granulation suitable for tablet manufacture in automatic machines.

Usually the granules are then lubricated with a lubricant which may be a water-insoluble soap such as magnesium stearate, calcium stearate, zinc stearate or other lubricants such as sodium stearate, stearic acid, talc, mineral oil, boric acid, sodium lauryl sulfate or calcium ricinoleate. The lubricant and the dry granules are mixed until homogeneous, and the composition is then ready to be compressed in a tablet compressing machine in accordance with the standard procedures. The tablets are firm, solid, completely satisfactory tablets which do not break under normal shipping conditions.

The combination of an ethyl cellulose binder and a lower alcohol is particularly advantageous because the granules are easily tableted with a minimum of pressure. The solvent is accepted without question in all pharmaceutical operations and the binder is stable, does not discolor sensitive materials, is completely free from odors and acceptable internally.

My new process is particularly useful with compounds such as ascorbic acid which, when tableted by conventional procedures, would turn brown and discolor after only a short storage period. When granulated in accordance with the present process, the ascorbic acid tablets will remain pure white indefinitely.

A mixture of sodium bicarbonate and tartaric acid may be granulated by my process to form tablets. The effervescent action on the addition of water to this mixture is well known. Other materials with which it is particularly advantageous to use an ethyl cellulose binder include such materials as antibiotics such as chlortetracycline, bacitracin, oxytetracycline, penicillin or mixtures of these, vitamin products such as ascorbic acid and thiamine, hygroscopic mixtures such as those containing citric acid or calcium cyanamide and many other pharmaceutical products such as 2-methyl-2-n propyl propanediol-1,3-dicarbamate(meprobamate).

Additionally, many compounds which have been previously tableted using gum acacia in water as a granulating agent may be granulated using ethyl cellulose as a binder and they will be found to be either more storage-stable or compatible in mixtures with materials which are water soluble. For purposes of convenience, ethyl cellulose may be used with all powders, even those which may be satisfactorily granulated with water in order to give a line of tablets which are completely uniform and consistent in all of their storage and solubility characteristics.

The following examples are illustrative of certain specific applications of my invention, all percentages being percent by weight unless otherwise specified. In the examples, the ethyl cellulose used is the commercial product referred to above.

EXAMPLE 1

Ascorbic acid tablets, 500 mg./tablet

	Percent
Ascorbic acid	79.2
Lactose	11.3
Ethocel	5.0
Corn starch powder	2.0
Alginic acid	1.5
Magnesium stearate	1.0
	100.0

99% isopropanol—18% by volume of total weight of solids.

The ascorbic acid, lactose and ethocel are mixed together with agitation. The isopropanol is sprinkled in while mixing, producing granules. After drying at 42° C. for six hours, the granules are screened through a No. 2 B Fitz screen. The remaining ingredients are added to the granules and the whole is mixed well. The material is then compressed into tablets.

EXAMPLE 2

Procaine penicillin, 250,000 u./tablet

	Percent
Procaine penicillin	49.0
Ethocel	1.0
White blank granulation for penicillin tablets ¹	47.3
Alginic acid	2.0
Magnesium stearate	0.7
	100.0

99% isopropanol—18% by volume of total weight of solids.

¹ CaCO₃—71%, CaH₂PO₄—14%, corn starch—13%, acacia powder—2%.

The penicillin and ethocel are mixed together and the isopropanol sprinkled in while mixing producing granules. After drying at room temperature (24° C.), these granules are screened as in Example 1. The granules plus the remaining ingredients are blended, in the order mentioned, and mixed well. The material is then compressed into tablets.

I claim:

1. In the process of granulating powders for tablet manufacture, the improvement which comprises the step of effecting granulation of the powder with a solution of from 0.5% to 10% of water permeable ethyl cellulose in a substantially water free lower alkanol solvent.
2. A process according to claim 1 in which the lower alkanol is ethanol.
3. A process according to claim 1 in which the lower alkanol is isopropanol.
4. A process according to claim 3 in which the powder contains ascorbic acid as a medicament.
5. A process according to claim 3 in which the powder comprises procaine penicillin.
6. In the process of granulating powders for tablet manufacture, the improvement which comprises mixing said powders in the dry state with from 0.5% to 10% by weight of water permeable ethyl cellulose and then adding a sufficient quantity of substantially water free lower alkanol to form a homogeneous paste.
7. A process according to claim 6 in which the lower alkanol is ethanol.
8. A process according to claim 6 in which the lower alkanol is isopropanol.
9. A process according to claim 8 in which the powder contains ascorbic acid as a medicament.
10. A process according to claim 8 in which the powder comprises procain penicillin.
